(57) **CLAIM**

The ornamental design for a vaporization tool, as shown and described.

DESCRIPTION

FIG. 1 is a top perspective view of a vaporization tool; FIG. 2 is a bottom perspective view of the vaporization tool of FIG. 1;

FIG. 3 is a top view of the vaporization tool of FIG. 1; FIG. 4 is a bottom view of the vaporization tool of FIG. 1; FIG. 5 is a first side view of the vaporization tool of FIG. 1; FIG. 6 is a second side view of the vaporization tool of FIG. 1;

FIG. 7 is a front view of the vaporization tool of FIG. 1; and, FIG. 8 is a back view of the vaporization tool of FIG. 1. The broken lines in the drawings depict portions of the vaporization tool that form no part of the claimed design.

1 Claim, 4 Drawing Sheets
